ABSTRACT

An electronic storage tube having a target which is composed of an insulating layer having an electrode on each surface thereof. One of the electrodes is overlaid on one of the surfaces of the insulating layer in a pattern of stripes or cross-stripes and the exposed areas of the insulating layer are scanned by electron beams to establish a storage charge pattern. Different potentials are applied to the two electrodes to cause them to operate in a wide dynamic range.

ELECTRONIC STORAGE TUBE

BACKGROUND OF THE INVENTION

1. Field of the Invention

The present invention relates mainly to an electronic storage tube and more particularly to the operation of a grid control type of storage tube using a storage target of insulating material which has electrodes on both surfaces thereof.

2. Description of the Prior Art

A conventional electron image storage device such as that disclosed in U.S. Pat. No. 3,631,294 is provided with a single storage target. In that tube an electron gun directs an electron beam at a target on the inner face of the tube. The target consists of an electrode layer of silicon with an insulating layer covering the surface of the electrode layer that faces the gun. The insulating layer has apertures in it through which electrons from the gun can reach the electrode.

The tube has four modes for each operating cycle: "ready," "writing," "read out," and "erase." In the "ready" mode, a relatively low voltage of about 20 volts is applied to the target and the potential on the side of the insulator facing the electron source is zero volts. To record a pattern of information over the surface of the target, the target voltage is raised to the "write" level of, for example, 200 volts. At this level, the secondary emission ratio of the apertured insulator layer is greater than unity, the voltage at the surface of the insulating layer facing the electron source will be 180 volts, which is the target voltage of 200 volts less the voltage difference of 20 volts that was present between the two surfaces of the insulator during the "ready" mode. Information is then stored, or written, by scanning the target surface with a beam of electrons from the electron source.

In the "read out" mode, the target voltage is reduced to, for example, 5 volts. Then, when the electron beam scans the target, some of its electrons will be repelled according to the stored charge pattern.

In the "erase" mode, the target voltage is again raised, for example to 200 volts, and the beam is caused to scan the surface again.

The reason why the "erase" process is thus necessary is that if the "erase" process were omitted and the "read out" process were directly followed by the "ready" process, the scanning carried out by a beam of low level of energy such as would be the case for a target voltage of 20 volts during the "ready" process, as mentioned above would require a long time to balance the surface potential V_s to zero volts across its entire surface. Accordingly, the written signal must be erased by such an "erase" process.

In the storage tube of the above construction, the larger the aperture area of the insulator layer, which is the same thing as saying that the larger the area of catching beams on the target electrode is, the larger the output of the tube is. On the other hand, if the aperture area is made large, the surface potential required to cut-off the beam at the "read out" time must have a large negative value. As a result, the maximum voltage across the insulating layer at the "write" time is required to increase. This means that the voltage across the insulating layer at the "ready" process must be made large. However, this voltage must also be made less than the withstanding voltage of the insulating

layer, which is the maximum permissible voltage that can be applied across it.

It is an object of this invention to provide an improved storage target for an electronic storage tube so as to produce a large output signal.

It is another object of this invention to provide a method of storing an image on a target of an electronic storage tube so as to have a high signal-to-noise ratio.

It is a further object of this invention to provide a method of storing an image on a target of an electronic storage tube in which the processes of one cycle from "write" to "ready" for the next writing are simplified.

It is a still further object of this invention to provide a method of storing an image on a target of an electronic storage tube in which the time from a "read out" condition to the completion of a "ready" condition for the next writing is shortened.

Further objects will be apparent from the following specification and drawings.

SUMMARY OF THE INVENTION

In the present invention, separate electrodes are provided on both major surfaces of a storage insulator to form a target. A voltage across the thickness of the insulator can be freely established for the simultaneous enforcement of "erase" and "ready" processes. Further, the potential range of storage areas on the surface of the insulator can be selected to be large, since a voltage applied thereto can be established in both polarities.

BRIEF DESCRIPTION OF THE DRAWINGS

FIG. 1 is a schematic cross-sectional view showing a conventional electronic storage tube;

FIG. 2 is an enlarged cross-sectional view showing a target of the storage tube of FIG. 1;

FIG. 3 is a graph showing the relation between secondary emission ratio of an insulator layer and target voltage which is used for its explanation;

FIG. 4 is a schematic cross-sectional view showing one example of a storage tube according to this invention;

FIG. 5 is an enlarged cross-sectional view showing the principal part of the target according to this invention;

FIG. 6 is a view showing the equivalent circuit of the target according to this invention;

FIG. 7 is an enlarged cross-sectional view of the principal part showing another example of the target according to this invention; and

FIGS. 8A-8E are process views showing one example of the method for fabricating the target according to this invention.

DETAILED DESCRIPTION OF THE INVENTION

In the tube in FIG. 1 which corresponds to that in U.S. Pat. No. 3,631,294, an electron beam emitting source, or an electron gun G is composed of a cathode K, a first grid G_1 , a second grid G_2 and a third G_3 . A voltage of, for example, -90 volts to zero volts is applied to the first grid G, in accordance with writing signals while constant voltages of 300 and 450 volts are applied to the second and thirds grids G_2 and G_3 , respectively. Reference numerals 2 and 3 indicate an alignment coil and a deflection coil, respectively. A target 4 is disposed on a face plate 1a of the tube envelope

1 and a beam landing adjusting grid G_4 located opposite the target 4.

As shown in FIG. 2, the target 4 comprises an electrode 5 on the inner surface of the face plate 1a of the envelope 1 and made of, for example, a silicon (Si) layer 5 and an insulator layer 6 made of silicon dioxide (SiO_2) which is formed by oxidizing the surface of the electrode 5. The insulator layer 6 has a plurality of apertures 7 formed by photo-engraving so that the electrode 5 is partially exposed therethrough at its surface.

A storage tube of such construction is operated by the repetition of four processes, that is, ready, write, read-out and erase.

A description will first be given of the "ready" process. In the "ready" process, a target voltage V_T applied to the electrode 5 is selected to be, for example, 20 volts with respect to the cathode K. The secondary electron emission ratio δ of the insulator layer 6 is made $\delta < 1$ and is varied according to the energy of electron beam bombarding it. This energy corresponds to the target voltage V_T as shown in FIG. 3. In the case of the SiO_2 layer 6, the ratio δ has values such as " $\delta < 1$ " when the voltage V_T is less than 40 volts and $\delta < 1$ when the voltage V_T is more than 40 volts. When the voltage $V_T = 20$ volts, making $\delta < 1$ as described above, the target 4 is scanned by an electron beam 8 emitted from the electron gun G. If the scanning is repeated, a potential V_s on the surface of the insulator layer facing the cathode K is balanced with the cathode potential at zero volts. As a result there will be a voltage $E_s = V_T - V_s$ between the opposite surfaces of the insulator layer 6. The voltage E_s can be selected to have a large value by selecting the voltage value of V_T to be large, but in the practical case this value is selected to be less than the withstand voltage of the insulator 6, for example about 20 volts.

At the next stage the "write" operation according to the aimed signal is carried out. To carry out the writing, the potential V_T applied to the electrode 5 is first selected to have a value to make the ratio δ of the insulator layer 6 $\delta < 1$, for example, 200 volts. If the potential V_T is thus selected to be 200 volts, the surface potential V_s of the insulator layer 6 will be such as $V_s = V_T - E_s = 200 - 20 = 180$ volts. When the electron beam 8 is subjected to density modulation in accordance with the writing signal under this condition, since the insulator layer 6 is in a condition showing $\delta < 1$, the surface potential V_s of the insulator layer 6 becomes more positive in response to beam density and finally increases to 200 volts. That is, the voltage V_s can be varied in a range of 180 to 200 volts according to the writing signal. Thus, the distribution of potentials according to the writing signals forms a pattern of potentials on the surface of the insulator layer 6. In this case, theoretically writing can be effected with the voltage V_s in a range between 180 and 200 volts, that is, within a range of 20 volts, but practically the voltage V_s is varied in a 15 volt range between 180 and 195 volts to maintain a linear characteristic. In other words, the writing is carried out as a potential pattern in which the voltage E_s applied to the insulator layer 6 typically $E_s = V_T - V_s = 200 - (180 \text{ to } 195)$, or between about 20 volts and 5 volts.

Next, this written pattern is read out as follows. At first, the target V_T is lowered to, for example, 5 volts. As a result, the surface potential V_s is changed with a distribution in accordance with the written pattern.

That is, since the written pattern is formed by the distribution of E_s , which is in the range from 5 to 20 volts, the surface potential V_s is distributed as a potential pattern in a range of $V_s = V_T - E_s = 5 - (5 \text{ to } 20) = 0$ to -15 volts. When the scanning is carried out by the electron beam 8 with the above condition, the beam moving through the aperture 7 of the insulator layer 6 to the target electrode 5 is modulated according to the distribution of the surface potential V_s of the insulator layer 6 so that it is restrained from reaching the electrode 5 at an area where the surface potential V_s has a large negative value to reduce a target current. That is, an output is obtained in accordance with the written pattern.

After the completion of the "read out" process, the written pattern is erased. In order to carry out the "erase" operation, the target voltage V_T is changed to a value at which the ratio of the insulator layer 6 can be $\delta < 1$, for example, 200 volts, and beam scanning is effected. Thus, the surface potential V_s is balanced with 200 volts which is the same as V_T and hence the voltage E_s becomes zero.

A description will now be given on one example of an electronic storage tube according to the present invention with reference to FIGS. 4 and 5. Elements of FIGS. 4 and 5 corresponding to those of FIGS. 1 and 2 are indicated by the same reference characters and without repeating their description.

In the present invention, a target 13 includes a target electrode 9 deposited on the inner surface of an insulating base plate or the face plate 1a of the tube envelope 1, an insulator layer 10 formed over the face plate 1a, and a signal electrode 12 formed on the layer 10 and having a plurality of small boxes or slit-like apertures 11 through which the insulator layer 10 is partially exposed. Thus, a capacitive element C is equivalently formed at each aperture 11 so that the electrode 12 is disposed adjacent to each capacitive element.

The target electrode 9 can be formed by vaporization of, for example, a layer of chromium Cr with a thickness of about 3,000 Å. The insulator layer 10 is formed in such a manner that the surface of the electrode 9 made of chromium is oxidized to a thickness of about several tens of Å to form chrome oxide (CrO) as its foundation. A layer of SiO or SiO_2 having a thickness of about 1 to 5 microns (μ) is vaporized on the CrO layer. Further, the signal electrode 12 is formed by vaporization of, for example, a layer of aluminum (Al) having a thickness of about 1,000 to 2,000 Å all over the surface. The apertures 11 are formed by photoengraving.

Operation of the storage tube according to this invention will now be described. At first, a condition ready for writing is established. In this condition the voltage V_T applied to the target electrode 9 is selected to be, for example, 200 volts, while the voltage V_p applied to the signal electrode 12 is selected to be 180 volts, or about 20 volts less than the voltage V_T . With electrodes at these voltages, an electron beam 14 is emitted from the electron beam emitting source or gun to scan the target. The secondary emission ratio δ of the insulator layer 10 is high enough so that $\delta < 1$ as described with reference to FIG. 3. As a result, the surface of the capacitive element C exposed through the aperture 11 and bombarded by the electron beam discharged secondary electrons, causing the surface to be positively charged. However, its surface potential V_s is balanced by 180

volts of the potential V_p of the electrode 12. That is, the potential V_s becomes equal to 180 volts. The reason that the surface potential V_s is balanced with the potential V_p is that, when the insulator layer 10 is bombarded at its surface by the electron beam, the secondary electrons are discharged to enhance the potential at that surface, causing the latter to become positive as described previously. However, if the potential V_s becomes higher than the potential V_p , the discharged electrons are repelled by the electrode 12 having the potential V_p to be combined with positive charge on the surface of the insulator layer 10, with the result that the surface potential V_s is not increased to a value higher than V_p but is finally balanced with the potential V_p . Accordingly, the voltage E_s applied to the capacitive element C in the aperture 11 formed by the insulator layer 10 becomes $E_s = V_r - V_s = 200 - 180 = 20$ volts. The voltage E_s can be freely chosen by the selection of the respective voltages V_r and V_p of the electrodes 9 and 12, but it is preferable that it be less than the withstanding voltage of the insulator layer. Hence, the voltages V_r and V_p are selected so as to make the voltage E_s , for example, 20 volts. Further, the voltage V_r should have a low enough value that the electron beam may be provided with enough energy to make the surface potential V_s equal to the potential V_p quickly by a small number of scannings.

With these voltages applied to the tube 1, the writing in response to the aimed signal is carried out. The voltage V_p applied to the signal electrode 12 is raised to a value higher than V_r , for example, to 220 volts, and the voltage V_r applied to the electrode 9 is kept at, for example, 200 volts. If the electron beam is subjected to density modulation in response to the writing signal under this condition in which the insulator layer 10 is in a condition such that $\delta < 1$, the surface potential V_s in the aperture 11 of the insulator layer 10 will be varied in a range from 180 volts, which was present during the "ready" process to the 220 volts applied to the electrode 12 at the present stage. The potential V_s will be 180 volts at areas where no writing is carried out by the electron beam but will be at the 220 volt maximum value at other areas where a great amount of electron beam is radiated. In this way, the surface potential V_s of the capacitive element C will be provided with a potential pattern that has a potential distribution of 180 to 220 volts as determined by the writing signal. Thus, in this invention, the surface potential V_s , which varies according to writing, can have a range of 40 volts, i.e., from 180 to 220 volts. Even though its linear characteristic is taken into consideration, the surface potential V_s is in a range of 35 volts, i.e., between 180 to 215 volts, which is substantially greater than the prior example that has a range of only about 15 volts, as described in FIGS. 1 and 2. However, attention must be paid to the fact that, although the writing range is 35 volts as mentioned above, the voltage applied to the insulator layer 10 is the difference between the voltage V_r , which is 200 volts, and the voltage V_p , which may be 220 volts, making the difference approximately equal to 20 volts between the opposite electrodes 9 and 12. The voltage applied to the capacitive element C or the voltage E_s across the thickness of the insulator layer 10 in the aperture 11 is $E_s = V_r - V_s = 200 - (180 \text{ to } 215) = 20 \text{ to } -15$ volts which means that the maximum voltage applied thereto is only 20 volts, so that all of the voltages applied to the respective por-

tions of the insulator layer 10 can be kept below the insulation breakdown voltage.

Next, in order to read out the written pattern, the potential V_r of the target electrode 9 is selected to be, for example, -20 volts and the voltage V_p applied to the signal electrode 12 is selected to be, for example, 10 volts. Since, at this time, the potential difference E_s across the thickness of the capacitive element C is distributed in a range of 20 to -15 volts for writing, the 10 surface potential V_s of each element C is distributed in a range of $V_r - E_s = -20 - (20 \text{ to } -15) = -40 \text{ to } -5$ volts or in a range of 35 volts. When the scanning is effected by the electron beam 14 under this condition, the electron beam 14 is modulated in accordance with 15 the surface potential V_s of each capacitive element C so that the electron beam may not easily reach the electrode 12 particularly adjacent to a portion of the element C where the surface potential V_s thereof has large negative value. Thus, the beam current is modulated 20 according to the written pattern, so that a signal output in response to the written pattern is derived from the signal electrode 12.

After the "read out" process, the written pattern is erased. This erasing operation can be carried out simultaneously with the "ready" process described above. That is, a voltage of 200 volts, for example, is applied to the target electrode 9 to make the secondary emission ratio of the insulator layer 10 $\delta < 1$ and to provide a high level of energy to the electron beam so that the 25 surface potential V_s of the capacitive element C can be quickly balanced with the potential V_p of the signal electrode 12. A voltage of 180 volts is applied to the signal electrode 12 to establish a predetermined potential difference E_s , for example, 20 volts between 30 the opposite ends of the capacitive element C.

After the "write" and "read out" operations are thus completed, the "ready" condition for the following writing can be rapidly established.

In the construction described above, the insulator 40 layer 10 is required to prevent the production of pinholes or the like, which might connect the electrodes 9 and 12. For this purpose it is desirable to make the insulator layer 10 as thick as possible. On the other hand, it is preferable for the insulator layer 10 to be 45 thin to make the capacitance of the element C large. In the target of the storage tube according to this invention the equivalent circuit of which is shown in FIG. 6, a stray capacity C_1 is formed between each capacitive element C and signal electrode 12. The surface potential V_s of the element C and the potential V_p of the electrode 12 are made equal in the "erase and ready" process, but in the "write" process they are made different and hence a potential difference V_1 is provided therebetween. Thus, the surface potential V_s is varied by the 50 influence from the voltage applied to the signal electrode 12 and its variation ΔV is given as

$$\Delta V = \frac{2C_1}{C} V_1$$

Accordingly, in order to make the variation as small as possible, it is necessary to make C_1 small and C large. For this reason, the insulator layer 10 forming the capacitive element C should preferably be thin as mentioned above.

In order to increase the capacity of the capacitive element C and to ensure the insulation between the elec-

trodes 9 and 12, the insulator layer 10 is constructed with thin portions 10A of thickness t_1 which forms the capacitive elements C and thick portions 10B of thickness t_2 which forms the electrodes 12 as shown in FIG. 7. The insulator layer 10 having portions 10A and 10B of different thickness t_1 and t_2 is constructed by making the insulator layer 10 so that its original thickness t_2 is relatively great. Sections of this thick layer 10 are partially etched away a required depth to form the portion 10A with a thickness t_1 . However, it is difficult to stop the etching at the required depth for the insulator layer 10 and to perform the etching with no side-etching being caused for the thick insulator layer. In this case, a special method is used in order to form the insulator layer 10 having a small thickness t_1 at one part and a large thickness t_2 at the other part. One example of this special method will now be described with reference to FIG. 8.

The target electrode 9 is formed by vaporization of, for example, chromium entirely on the substrate or face plate 1a. Then, on the electrode 9 there are successively deposited more than two layers, for example, first, second and third insulating layers 10a, 10b and 10c by utilizing a well known technique such as a thermal cracking method or the like (FIG. 8A). The first insulating layer 10a is formed of a material providing a large value of the secondary emission ratio δ by the bombardment of electrons having a proper level of energy. For example, the layer 10a may be MgF_2 , CaF_2 or the like deposited on the face plate 1a with the thickness t_1 , for example, 5,000A suitable for constructing the capacitive element C as described in connection with FIG. 7. The second insulating layer 10b is formed by depositing on the layer 10a a material which is capable of being etched differently from the first insulating layer 10a and provides almost no corrosion to the first insulating layer 10a by its etching liquid, for example, Al_2O_3 . The thickness of the second layer 10b may be, for example, 5,000A. Further, the third insulating layer 10c, made of such a material different from those of the first and second insulating layers 10a and 10b but capable of being etched is formed by deposition on the layer 10b. The layer 10c may be SiO_2 having a thickness of about 1μ . The material of this layer is also not corroded substantially by the etching liquids for the first and second insulating layers. The total thickness of the first, second and third insulating layers 10a, 10b and 10c is equal to the large thickness t_2 required between the both electrodes 9 and 12 as described in connection with FIG. 7.

On the third insulating layer 10c, there is deposited a metal layer 12' which finally forms the electrode 12 (FIG. 8B). The metal layer 12' can be formed by vaporization, of, for example, a gold layer on a chromium layer.

On the metal layer 12' excepting portions where the apertures 11 of the electrode 12 are formed therethrough, there is deposited by optical processing a photo resist 15 that serves as an etching resist to the metal layer 12' (FIG. 8C).

The metal layer 12' is etched, except where covered by the resist 15, to remove unnecessary portions and thereby form the electrode 12 (FIG. 8D).

Next, with this electrode 12 being used as a mask, the third insulating layer 10c made of, for example, SiO_2 is etched by fluoric acid to form an aperture 16 inside the aperture 11. Further, with this third insulating layer 10c

being used as a mask, the second insulating layer 10b is etched through the aperture 16 by an etching liquid, for example, heated phosphoric acid to provide an aperture 17 coincident with the aperture 16 (FIG. 8E). At this time, the first insulating layer 10a is not corroded by the etching liquid for the second insulating layer 10b, so that the layer 10a remains as it is.

According to the above described method, between the opposite electrodes 9 and 12 the respective insulating layers 10a, 10b and 10c remain as they are to form the insulator layer 10 with the large thickness t_2 equal to the sum of those of the respective layers, so that the insulation between the electrodes 9 and 12 can be positively maintained. At areas forming the capacitive element C inside the aperture 11 of the electrode 12, the insulator layer 10 is formed with the small thickness t_1 equal to that of the single insulating layer 10a by a recess 18 formed with the apertures 16 and 17, so that the capacity of the capacitive element C can be made large.

However, the portion between the electrodes 9 and 12 is formed not by the single insulating layer with large thickness but by a plurality of different insulating layers being overlapped successively and hence there is little possibility that the pinholes or defective portions in the layers 10a, 10b and 10c will be coincident with one another so as to connect the electrodes 9 and 12 and cause a troublesome short-circuit between the electrodes 9 and 12.

When the above described method is used, the insulator layer 10 is formed by overlapping the insulating layers 10a, 10b and 10c that respond to different etching liquids. Accordingly, even though a deep recess 18 is formed inside the aperture 11 of the insulator layer 10, it is possible to prevent the recess 18 from being enlarged by side-etching. In addition, since the thickness t_1 of the portion forming the capacitive element C is defined by the thickness of the insulating layer 10a, in the case of forming the recess 18 high accuracy in control of the etching process is not necessary for the control of its depth. Thus, the uniformity of productivity and characteristics of the targets can be improved.

The method for concretely forming the target 13 and its construction are not limited to the above-mentioned example. The face plate of the tube envelope is used as the base plate in the foregoing example, but it is also possible for electrodes to be vaporized on opposite surfaces of a base plate, for example, a glass plate about 40μ thick. Thereafter the exposed surface of the signal electrode side is etched about 1 to 2μ to form a target which is attached to the face plate.

According to this invention, separated from the target electrode 9 there is also provided the signal electrode 12 to which the potential V_P different from the target potential V_T if applied. This has several advantages. For example, the "erase" and "ready" processes can be carried out at the same time, though they may be effected separately. In other words, the potential V_T of, for example, 200 volts is applied to the electrode 9 while a potential V_P of 180 volts is applied to the electrode 12. With such an arrangement, an electron beam having a large level of bombarding energy is emitted to erase the previously written information quickly and to complete the "ready" condition in which the voltage E_s of about 20 volts is applied to the capacitive element C. Accordingly, the drive and circuit arrangement to be used with the tube of this invention can be simplified

and also the time period from "read out" to the beginning of following writing can be shortened.

Further, when the writing is carried out, the potential V_p of the electrode 12 can be raised to a value different from that of the electrode 9, for example, 220 volts. Thus, the writing can be made on the capacitive element C in a range between positive and negative voltages with the potential of the electrode 9 as the reference therebetween, so that a voltage range more than twice that of the conventional storage tube can be theoretically provided. The writing can be effected in a range of better linearity and also in the case of "read out" process the information can be derived as a large output, so that the signal-to-noise ratio can be enhanced. In addition, irrespective of the large output, the voltage applied to the insulator layer 10 can be made lower than its insulation break-down voltage at the respective portions.

Further, the storage tube according to this invention is not limited to the storage of electric charge but can be used as a light-electricity transducer, that is, as an image pickup tube. In the latter case, a target electrode is formed by a transparent conductive layer such as NESA, while a storage insulating layer is formed by a photoconductive layer such a three-element compound of As-Sb-S on which a signal electrode of mesh type or stripe-type is formed. Thus a target is provided. In the "ready" process, a voltage of, for example, 30 volts is applied to the target electrode while the signal electrode is energized with, for example, zero volts. The target is then scanned by an electron beam. In the "write" process, an optical pattern is projected from the side of transparent electrode. The amount of light causes the photoconductive layer to change its resistance, thereby changing its surface potential. The surface potential approaches 30 volts at areas where no light is projected. On the other hand, in the "read out" process, the target electrode is energized by a voltage of, for example, zero volts while the signal electrode is energized by a voltage of, for example, 5 volts. When the scanning is carried out by an electron beam under the latter condition, a current according to the optical pattern can be derived from the signal electrode. This system is not of a type in which the charging and discharging currents of a capacitance in the photoconductive layer are read out as in the case of vidicon. This system is of a grid control type, so that the "read out" operation can be repeatedly carried out.

What is claimed is:

1. A storage tube comprising:

A. a target comprising:

1. a first conductive layer,

2. an insulating layer thereon, and

3. a second conductive layer, said second conductive layer comprising a pattern of apertures through which said insulating layer is directly exposed; the insulating layer being thinner at regions corresponding to each of said apertures than at regions covered by solid portions of said second conductive layer;

B. an electron source to direct electrons at said second conductive layer and the exposed portions of said insulator layer; and

C. means to apply different potentials to said first and second conductive layers to establish, selectively, conditions for recording a charge pattern of electrons from said source on said insulating layer and

for reading said pattern and for erasing said pattern.

2. The storage tube of claim 1 in which said insulating layer comprises a plurality of layers of insulating material responsive to different etching materials whereby selected areas of said insulating layer may be etched to controlled depths.

3. A method of storing an image in a storage tube comprising electron emitting means and a target including a storage material having first and second surfaces, a first electrode provided on said first surface of the storage material, and a second electrode partially provided on said second surface of the storage material, said second surface having a storage area to be scanned by an electron beam from said electron emitting means, said method comprising the steps of: applying first and second potentials to said first and second electrodes, respectively, the first and second potentials having a value sufficient to cause secondary electron emission from said storage area when scanned by said electron beam but the potential difference therebetween being less than the breakdown voltage of said storage material, to make said storage area substantially the same potential; applying third and fourth different potentials to said first and second electrodes, respectively, to establish a charge pattern on said storage area; and applying fifth and sixth potentials to said first and second electrodes, respectively, to detect said pattern.

4. A method of storing an image on a target according to claim 3 wherein a reference potential is applied to said electron emitting means.

5. A method of storing an image on a target according to claim 3 wherein said first potential is higher than said second potential to provide a potential difference between said surfaces of the material.

6. A method of storing an image on a target according to claim 4 wherein said third and fourth potentials are sufficiently higher than said reference potential to cause secondary electron emission from said storage area.

7. A method of storing an image on a target according to claim 6 wherein said fourth potential is higher than said third potential.

8. A method of storing an image on a target according to claim 4 wherein said fifth potential is lower than said reference potential.

9. A method of storing an image on a target according to claim 8 wherein said sixth potential is higher than said reference potential.

10. A method of storing an image on a target according to claim 3 wherein said storage material is a photoconductive material and said first electrode is transparent.

11. A method of storing an image on a target according to claim 10 wherein said charge pattern depends on incident light.

12. A method of storing an image in a storage tube comprising electron emitting means and a target including a storage material having first and second surfaces, a first electrode provided on said first surface of the storage material, and a second electrode partially provided on said second surface of the storage material, said second surface having a storage area to be scanned by an electron beam from said electron emitting means, said method comprising the steps of: applying first and second potentials to said first and second

electrodes, respectively, the first potential being greater than the second potential, to make said storage area substantially the same potential when scanned by said electron beam; applying third and fourth potentials to said first and second electrodes, respectively, the fourth potential being greater than the third potential and being of sufficient value to cause secondary emission from said storage area when scanned by said electron beam so as to establish a charge pattern on said storage area; and applying fifth and sixth potentials to said first and second electrodes, respectively, to detect said pattern.

13. A method of storing an image in a storage tube in accordance with claim 12 wherein said established charge pattern has a potential distribution within a range defined by the difference between said second and fourth potentials.

14. A method of storing an image in a storage tube comprising electron emitting means and a target including a storage material having first and second surfaces, a first electrode provided on said first surface of the storage material, and a second electrode partially provided on said second surface of the storage material, said second surface having a storage area to be scanned by an electron beam from said electron emitting means, said method comprising the steps of: applying first and second different voltage potentials to said first and second electrodes, respectively, to make said storage area substantially the same potential when scanned by said electron beam; applying third and fourth different potentials to said first and second electrodes, respectively, so as to establish a charge pattern on said storage area; and applying fifth and sixth different potentials to said first and second electrodes, respectively, the difference between said fifth and sixth

potentials being at least as great as the range of the potential distribution corresponding to said charge pattern on said storage area.

15. A method of storing an image in a storage tube comprising electron emitting means and a target including a storage material having first and second surfaces, a first electrode provided on said first surface of the storage material, and a second electrode partially provided on said second surface of the storage material, said second surface having a storage area to be scanned by an electron beam from said electron emitting means, said method comprising the steps of: applying first and second potentials to said first and second electrodes, respectively, the first potential being greater than the second potential and having a value sufficient to cause secondary electron emission from said storage area when scanned by said electron beam, but the difference between said first and second potentials being less than the breakdown voltage of said storage material, to make said storage area substantially the same potential; applying third and fourth potentials to said first and second electrodes, respectively, the fourth potential being greater than the third potential and being of sufficient value to cause secondary emission from said storage area when scanned by said electron beam so as to establish a charge pattern on said storage area having a potential distribution within a range defined by the difference between said second and fourth potentials; and applying fifth and sixth potentials to said first and second electrodes, respectively, the difference between said fifth and sixth potentials being at least as great as said range of potential distribution on said storage area.
